UNITED STATES PATENT OFFICE

129,595

DESIGN FOR A NEWEL POST FOR BOWLING ALLEYS

Alfred Reiss, Newton, Mass.

Application April 9, 1941, Serial No. 100,263

Term of patent 7 years

To all whom it may concern:

Be it known that I, Alfred Reiss, a citizen of the United States, residing at Newton, in the county of Middlesex and State of Massachusetts, have invented a new, original, and ornamental Design for Newel Posts for Bowling Alleys, of which the following is a specification, reference being had to the accompanying drawing, forming part thereof.

Figure 1 is a perspective view of a newel post for a bowling alley, showing my new design. Figure 2 is an edge elevational view thereof and Figure 3 is a top plan view on a reduced scale.

I claim:

The ornamental design for a newel post for bowling alleys, as shown.

ALFRED REISS.
